UNITED STATES PATENT OFFICE.

LAWRENCE V. CALHOUN, OF GLENELLYN, ILLINOIS, ASSIGNOR TO SEARS, ROEBUCK & COMPANY, OF CHICAGO, ILLINOIS, A CORPORATION OF NEW YORK.

FOLDING GRINDSTONE-FRAME.

1,210,145.

Specification of Letters Patent.

Patented Dec. 26, 1916.

Application filed September 7, 1916. Serial No. 118,905.

To all whom it may concern:

Be it known that I, LAWRENCE V. CALHOUN, a citizen of the United States, residing at Glenellyn, in the county of Dupage and State of Illinois, have invented a new and useful Improvement in Folding Grindstone-Frames, of which the following is a specification:

My invention relates to certain new and useful improvements in folding grindstone frames, and more particularly to the construction of the hinge joint or bearing support of the frame.

The invention will be more fully understood from the following detailed description, taken in connection with the accompanying drawings, in which:—

Figure 1 is a perspective view of a folding grindstone frame embodying the invention; Fig. 2 is a side elevation, enlarged, of one-half of the hinge and the bearing, the other half of the hinge being shown in dotted lines; Fig. 3 is a side elevation of the opposite half of the hinge; Fig. 4 is a section on the line 4 of Fig. 2, and Fig. 5 is a section on the line 5 of Fig. 2.

Referring more particularly to the drawings, the numeral 10 designates the front pair of supporting legs, and the numeral 11, the rear pair of supporting legs of the grindstone frame. The legs 10, 11, on each side are secured at their upper ends to a hinge-joint construction, generally designated by the numeral 12. The two hinge-joint members support bearings for the arbor of a grindstone 13, the projecting end of the arbor being provided with cranks, so that the stone may be driven as by a pair of treadles 14 and connecting rods 15. The operator's seat designated 16, is supported by a pair of horizontal arms 17, the front ends of which are attached to the hinge-joint members 12, and the rear ends of which are secured to struts 18, mounted upon the legs 11. A guard 19 is also carried by the horizontal arms 17 just in front of the seat 16.

The hinge-joint 12 to which the present invention is more particularly directed is illustrated in detail in Figs. 3 to 5, from which it may be seen that this member consists of a pair of hinged castings, designated 20 and 21, respectively, each having a pivot bolt opening therein, the member 20 having a squared recess surrounding the pivot bolt

opening, and designated 22, and the member 21 having a mating lug adapted to loosely fit within the recess 22 and designated 24. In the assembled position of the parts as shown in Fig. 5, the pivot bolt 23 passes through the openings in the hinge member castings, the lug 24 and recess 22 serving to limit the relative movement of the two members.

To support the bearings for the grindstone arbor, the hinge members 20, 21, are each provided with a quadrant-shaped seat, designated 25, and having a shoulder or flange 26 at the outer end. In the assembled position of the parts as shown in Fig. 2, the two quadrant-shaped seats 25 oppose one another, being slightly spaced apart at the bottom and extending therefore around somewhat more than 180° of the bearing bushing 27 which they receive. Instead of being bored centrally, as is commonly the case, the bushing 27 is bored eccentrically, as indicated at 28, and so mounted in the supporting members 20, 21, that the center of the bore 28 lies directly below the center of curvature of the quadrant-shaped seats 25. The upper or thicker portion of the bushing 27 is centrally drilled and tapped to receive a grease cup 30 and the grease cup may be made use of to secure in place a light stamped metal cap piece 31.

In assembling the grindstone frame the hinge portions 12 are arranged with the flanges or shoulders 26 facing outwardly so that the bearing bushings 27 are held against axial movement in this direction, the stone itself serving to prevent their inward movement. The lug and recessed lock joint by which the relative movement of the hinge members is limited is purposely constructed so loose that the weight of the grindstone will cause the seats 25 to pinch the bearing bushing 27. Since these seats extend over more than 180° of the periphery of the bushing, the latter is therefore positively locked in place by the mere act of assembling the parts. Furthermore, it should be noted that since the bushing has its bearing portion bored eccentrically, the weight of the grindstone itself tends to prevent the bushing from rotating in its seat. The lug and recess construction by which the relative movement of the hinge members is limited is particularly desirable as tending to remove the strain from the pivot bolt and further because of the fact

that even should the grindstone and its bearings be removed the frame would still maintain its approximate form.

While I have shown and described in considerable detail one specific embodiment of my invention, it is to be understood that this showing and description is illustrative only and for the purpose of making the invention more clear, and that I do not regard the invention as limited to these details nor to any of them, except in so far as such limitations have been included within the terms of the following claims, in which it is my intention to claim all novelty inherent in the invention as broadly as is permissible in view of the prior art.

What I claim as new and desire to secure by Letters Patent is:

1. In combination, a hinge member and bearing support for a folding grindstone frame, comprising a pair of pivoted leg members having seat portions adapted to embrace a cylindrical bearing bushing arranged on the opposing faces of their upper ends, and a bushing lying in the seat formed by the said portions, whereby downward pressure upon the bushing will cause the latter to be grasped by the seat portions.
2. A hinge member and bearing support for a folding grindstone frame and comprising a pair of leg members hinged together intermediate their lengths, the said members having seat portions adapted to embrace a bearing bushing arranged on the opposing faces of their upper ends and extending around more than 180° of the periphery of the bushing, and a bushing lying

in the said seat portions, whereby downward pressure upon the bushing will cause the latter to be grasped and locked in place by the 40 said seat portions.

3. A hinge member and bearing support for a folding grindstone frame and comprising a pair of leg members, a pivot bolt securing said leg members in hinged relationship, means for limiting the relative movement of said leg sections, bearing seat portions carried by said legs above said pivot bolt, and a cylindrical bearing bushing mounted in said seat, the relative movement 45 of said leg members being sufficient to permit them to grasp the said bushing.

4. In combination a bearing support having a cylindrical bearing seat therein, and a bearing bushing mounted for rotation in the 55 said seat, the said bushing having its internal bore eccentric to its outer cylindrical surface.

5. A hinge member and bearing support for a folding grindstone frame and comprising, in combination, a pair of leg sections, a non-circular lug formed on one of said sections, and a mating recess formed in the opposite section, said lug and recess fitting loosely to permit a limited hinging movement of the two sections, a pivot bolt securing the two sections together and holding the said lug in engagement with the said recess, quadrant-shaped cylindrical seats arranged facing one another on the upper ends 65 of said leg-sections, and an eccentrically bored bearing bushing mounted in the said seats.

LAWRENCE V. CALHOUN.
